UNITED STATES PATENT OFFICE.

SAMUEL DIXON, OF BIRMINGHAM, ALABAMA.

POST-HOLE-DIGGING MACHINE.

1,036,584.

Specification of Letters Patent. Patented Aug. 27, 1912.

Application filed May 4, 1912. Serial No. 695,097.

To all whom it may concern:

Be it known that I, SAMUEL DIXON, a citizen of the United States, residing at Birmingham, in the county of Jefferson 5 and State of Alabama, have invented a new and useful Post-Hole-Digging Machine; and I do hereby declare the following to be a full, clear, and exact description of the invention, such as will enable others skilled 10 in the art to which it appertains to make and use the same.

This invention relates to a new and useful post hole digging machine.

The principal object of the invention is to 15 provide a machine of this nature, in which various essential, desirable, and practical features of construction exist.

The various features of construction are 20 hereinafter set forth, shown in the drawings and claimed.

In the drawings:—Figure 1 is a view in perspective showing the improved machine constructed in accordance with the invention, and showing the auger in a raised position. Fig. 2 is a sectional view through the machine, showing the auger completing the drilling of a post hole. Fig. 3 is a plan view of a foot treadle device for throwing a rack in mesh with a gear.

As to the accompanying drawings 1 designates the base frame, which comprises the beam 2 and the handle beams 3 and 4. Connecting the handle beams 3 and 4 is a transverse beam 5, and extending downwardly 25 from the handle beams 3 and 4 are the legs 6. Secured to and projecting downwardly from the beam 2 are the bearing brackets 7, in which the axle 8 is journaled. Mounted on the axle 8, one upon each end, are the 30 supporting wheels 9, whereby the machine may be moved from place to place. Vertical standards 10 are provided having feet 11, which are secured by bolts or other means 12 to the beam 2. The standards 10 rise vertically from the beam 2, and their 35 upper ends terminate in restricted threaded portions 13, which penetrate the connecting bar 14, and receive the nuts 15. Connecting between the bar 14 and the handle beams 40 are the brace bars 16 and 17, which are secured in position as at 18 and 19. However, the brace bar 17 terminates in an integral tooth rack 20. The metal 21 which 45 integrally connects the rack 20 to the bar 17 is of resilient character, so that the rack will 50 spring in the position shown in full lines

in Fig. 2. The lower portion of the rack 20 terminates in a spring foot 22, which by bearing against the handle beam 4 assists in steadyng the rack in engagement with 55 the pinion, while the resilient or spring portion 21 tends to throw the rack in the position shown in full lines in Fig. 2. The purpose of this rack 20 will presently appear, as the invention is further described. A 60 vertical movable frame 23 is provided, which comprises the upper and lower bars and the intermediate bar 24, 25 and 26 and the end rods 27. Projecting laterally of the end rods 27 are the projections 28 and 29, which terminate in spherical bearings 30, which are sleeved slidably on the standards 10, so that the frame 23 may be raised and lowered vertically.

Journaled in bearings 31 of the end rods 75 27 of the frame 23 is a shaft 32, each end of which terminates in a crank 33 having a handle 34. Movable with the shaft 32 is a beveled pinion 35, which meshes with a similar beveled pinion 36 upon the upper 80 end of the shank 37 of the auger 38. The auger shank extends through a bearing 39 of the bar 25, so as to revolve therein. This bearing 39 is provided with a race-way 40 in its upper surface, and one in its lower 85 surface. Secured as at 42 to the auger shank are the annular plates 43 and 44, which are provided with race-ways 45 and 46, to cooperate with the ball bearing 47, between the bearing 39 and the plates 43 and 44. 90 The upper end portion of the auger shank is mounted in the bearing 49.

Revolute with the shaft 32 is a spur pinion 50 adapted to mesh with the teeth of the rack 20, so that the frame 23 will lower, 95 when the shaft 32 is rotated by virtue of the cranks 34, and will also raise or move in a reverse direction. However, the frame 23 will gradually lower, without the intermeshing of the pinion 50 and the teeth of 100 the rack 20, because after the auger 38 has secured a hold in the ground, the threads thereof, as the auger further enters the ground will pull the frame 23 downwardly. The frame 23 will best move downwardly 105 when the pinion 50 and the rack 20 intermesh. To cause the rack to intermesh with the pinion 50 pressure may be applied upon the foot treadle 51, which is pivoted in the bracket plate 52, as at 53. When pressure 110 is applied upon the treadle 51, the end 54 thereof engages the tail end 55 of the bar

56, which is pivoted at 57 in the bracket plate 58. When the end 54 and the tail end 55 engage in this manner, the end portion 59 of the bar 56 moves downwardly 6 against the action of the spring 60, and cams against the rack 20, thus forcing the teeth thereof in mesh with the teeth of the pinion 50. The foot treadle 51 is distorted laterally, so as to be free of the brace 10 bar 17.

In digging post holes the machine is positioned so that the auger will enter the ground at the desired location. Then motion is imparted to the shaft 32, which will 15 not only rotate the auger through the gears 35 and 36, but will cause the frame 23 to descend by the intermeshing of the pinion 50 and the rack 20. As before stated it is not absolutely necessary to use the rack 20 20 to cause the frame 23 to descend. However, to cause the frame 23 to ascend, so as to remove the auger from the hole, the rack 20 should be thrown in mesh with the gear 50, by depressing the foot treadle 51.

25 The invention having been set forth, what is claimed as new and useful is:—

1. In combination, a portable base frame having a guide frame rising therefrom, a vertical movable skeleton frame guided upon the guide frame and having a boring mechanism, a revoluble shaft mounted in the skeleton frame and having gear connections with the boring mechanism, a spur pinion, a tooth rack having a resilient connection 30 with the upper portion of the guide frame 35 and terminating in a resilient foot adapted to engage the base frame to assist in steady- 40 ing the rack when in engagement with the pinion, and a manually operated device adapted to throw the rack in engagement with the pinion.

2. In combination, a portable base frame having a guide frame rising therefrom, a vertical movable skeleton frame guided upon the guide frame and having a boring mechanism, a revoluble shaft mounted in the skeleton frame and having gear connections with the boring mechanism, a spur pinion, a tooth rack having a resilient connection with the upper portion of the guide frame 45 and terminating in a resilient foot adapted to engage the base frame to assist in steady- 50 ing the rack when in engagement with the pinion, a pivoted bar mounted on the base frame to be operated so as to cam against 55 the rack bar to throw it in mesh with the pinion, a spring for holding the camming end of the pivoted bar in a raised position, and a foot treadle mounted on the base frame for operating the pivoted bar. 60

In testimony whereof I have signed my name to this specification in the presence of two subscribing witnesses.

SAMUEL DIXON.
